UNITED STATES PATENT OFFICE.

ALFRED L. SOHM, OF CHICAGO, ILLINOIS, ASSIGNOR TO SOHM ELECTRIC SIGNAL & RECORDING COMPANY, OF CHICAGO, ILLINOIS, A CORPORATION OF ARIZONA.

ELECTRICAL CIRCUIT-CHANGING MECHANISM.

1,138,990.

Specification of Letters Patent. Patented May 11, 1915.

Application filed April 15, 1912. Serial No. 990,864.

To all whom it may concern:

Be it known that I, ALFRED L. SOHM, a citizen of the United States, residing at Chicago, in the county of Cook and State of Illinois, have invented a certain new and useful Improvement in Electrical Circuit-Changing Mechanism, of which the following is a full, clear, concise, and exact description, reference being had to the accompanying drawings, forming a part of this specification.

My invention relates to electrical circuit changing mechanism and is particularly concerned with contact mechanism to be operated under the step by step system. I contemplate the use of my device particularly in connection with recording apparatus for registering elapsed time and it will be seen that my invention is particularly adapted to this purpose. In the employment of devices of this kind it is frequently necessary to operate a large number of them at a time and it is therefore consistently my object to provide means which will operate effectively whether one or more are simultaneously connected to the motor. It is furthermore desirable that the contact mechanism be controlled in this connection with the motive device, from a distance, and I therefore provide means for electromagnetically controlling this operative connection. Broadly, what I do is to operate the contact mechanism by common means and control it by individual electromagnetic means.

While it may be found that my invention is practicable for other purposes, I contemplate particularly its use as a means for keeping track of the working time of employees in large industrial establishments. It will be seen that the refinement of my invention is directed toward this use. It is usual in large industrial establishments to provide means by which a record of the working time of the employees is made by requiring the employees to register the beginning times and the ending times of their respective working periods. This is usually done by requiring each employee to register, each time that he enters and leaves the premises, upon a time-clock or "in and out" device, as it is often called. Such operations, in industrial parlance, are called "punching the clock" and the practice has become one of almost universal employment.

In connection with a plurality of my devices, therefore, I provide an entrance plate, with electric switches to be manipulated by the employees, and a recording machine which is adapted for association with any of these devices, so that a record of the time accumulated may be made. Broadly, the result secured is this: Whenever an employee goes to work, he operates a switch. Whenever he stops work he operates a switch. During the time that he is working the step by step electrical contact mechanism advances and "accumulates" or integrates the time.

The recording machine may be connected with any "accumulator," as I have called my device, to make a record of the integration up to that point. Incidentally, I provide means whereby a visual indication is had at all times. The accumulator or circuit changing mechanism is a special device and it is this device to which the present application is directed. I shall confine my specific description to the circuit changing mechanism and shall refer to the system in which it may be employed merely broadly and merely to illustrate the utility of my invention.

The particular object of my present invention is to secure such step by step contact mechanism which, as before stated, may be operated to equal advantage either singly or conjointly, which is simple in construction and which may be formed as a unit so as to facilitate inspection and repair and so as to facilitate the expansion of a recording system.

Other features are special improvements and there are details of construction which are important and which are made the subject-matter of the more specific of the appended claims.

My invention is illustrated in the accompanying drawings, in which—

Figure 1 is a front elevational view of part of a bank of my devices, parts being broken away to reveal the interior construction; Fig. 2 is a plan view of my device, the casing for the contacts being shown in section to illustrate the interior construction; Fig. 3 is a view taken approximately on the plane of the line 3—3 of Fig. 2 and looking in the direction indicated by the arrows; Fig. 4 is a side elevational view of my de-

vice, part of the view being a section taken on the plane of the line 4-4 of Fig. 2 and looking in the direction indicated by the arrows; Fig. 5 is a front face view of one set of contacts; Fig. 6 is a rear face view of one of the wipers; Fig. 7 is a sectional view taken on the plane of the line 7-7 of Fig. 2 and looking in the direction indicated by the arrows; Fig. 8 is a partial view taken on the plane of the line 8-8 of Fig. 2 and looking in the direction indicated by the arrows; and Fig. 9 is a diagrammatic view illustrating the manner in which my device may be connected up in circuit.

15 Like reference characters are applied to the same parts throughout the various figures.

The various operating parts of my device are conveniently carried together and upon 20 the frame-piece 10, of U-shaped cross-section, which may be secured in place in a suitable case in any suitable manner. This frame-piece 10 as clearly illustrated in Figs. 2 and 7, receives an insulating block 11 25 which may be secured in place by means of screws 12, 12. On the back of the frame-piece 10 three bosses 13, 13 are provided and these bosses provide suitable bearings for the shafts 14, 15 and 16. In the particular 30 device herein disclosed, I shall refer to the shaft 14 as the fraction shaft, to the shaft 15 as the units shaft, and to the shaft 16 as the tens shaft. Each of the shafts 14, 15 and 16 carries at its forward end a wiper 35 17 insulated by means of the insulating spool 18 and held in place by a clamping screw 19. Incidentally, a number disk 20 is also clamped in place with the wiper by means of the clamping screw 19, as is also 40 a thumb-screw 21. The wiper 17 is provided with a part 17^a cut from the center thereof and sprung inwardly as clearly illustrated in Fig. 7. The main part of the wiper is adapted to always ride in contact 45 with a ring 22 disposed in the block 11 concentrically with the shaft 15. The part 17^a of the wiper is adapted to ride over and engage a series of circularly arranged contact pins 23 which are screwed in from the 50 back of the block 11 and passed through enlarged openings 24, 24 in the back of the frame-piece 10. It will be seen that by screwing in these pins more or less, the proper adjustment may be secured in order 55 that the wiper part may make the proper engagements. A cover 25 covers the parts which have just been described, there being openings therethrough for the passage of the thumb-screws 21 and also properly disposed openings 26, 26 for the exposure of 60 one of the numbers on the number disk 20 as best illustrated in Fig. 1. The frame-piece 10 is secured to a pair of rearwardly extending posts 27, 27 which form bearings 65 for the longitudinally extending shaft 28

held against displacement by means of a set collar 29. This shaft is periodically advanced by means of time controlled spring mechanism 30, of any desirable kind.

Mechanism is provided for kinematically 70 connecting the shafts 14, 15 and 16, with the shaft 28 so that the motion of the motor 30 may be transmitted thereto. The shafts 16 and 15 are connected with the shaft 14 through the medium of Geneva mechanism, 75 as will be described presently, and the shaft 14 is adapted to be connected with the shaft 28 through the medium of an electromagnetically operated clutch which is constructed as follows: The post 27 carries a 80 bracket 31 to which the frame 32 of magnetic material is secured by means of screws 33, 33. A core 34 is mounted upon the frame 32 and an energizing winding 35 is mounted upon this core. An armature 36, 85 pivoted at 37 to the frame, is mounted at the forward end of the core 34, subject to its influence, and a spring 38, disposed in a contact in the forward end of said core, tends normally to throw the armature 36 90 out to the position shown in dotted lines in Fig. 4. Upon the top of the frame 32 a lever arm 39 is pivoted at 40 and the forward end of this arm is provided with a hook 41 which, when the armature 36 is 95 drawn up, is held in engaging position holding the armature by means of a spring 42 disposed between the tail of the lever arm 39 and the frame. A second core 43 is mounted on the frame 32 and this core 100 carries an energizing winding 44. The core 43 is provided with an armature 45 which is secured to the tail of the lever arm 39 and when the winding 44 is energized, the armature 45 will be brought down to 105 raise the hook 41 and to allow the spring 38 to throw back the armature 36.

The shaft 14, as illustrated in Fig. 4, lies in the plane of the shaft 28 and is extended almost to that shaft. On this extension, the 110 gear wheel 46 is splined so as to rotate therewith, and a collar 47 is loosely mounted upon the shaft 14 beyond the gear wheel and is provided with a yoke 48 which straddles the shaft 28 and which engages in a 115 pocket 49 in the face of the armature 36. A tooth disk 50 is also secured upon the shaft 14 and a spring 51 disposed between the tooth disk and the gear 46 tends to force the gear rearwardly and to hold the yoke 48 in constant engagement in the pocket 49 in the armature. The tension of the spring 51, however, is designed to be overcome by the tension of the spring 38, so that when the armature 36 is released it will be free to move forwardly. When the winding 35 is energized and the armature 36 is drawn up, the spring 51 is free to act and to move the gear wheel 46 into engagement with the pinion 52 secured in proper position upon the 120 125 130

shaft 28. It will thus be seen that when the winding 35 is energized, the gear and the pinion will be brought into operative relation and that when the winding 44 is energized they will be brought out of such relation. It will be seen that the wiper rotates with the gear 46 and thus the connection between the wiper and the driving means is controlled electromagnetically.

10 The tooth disk 50 is in mesh with the cam disk 53 secured upon the shaft 15, the tooth 50^a on the disk 50 being adapted to coöperate with the slots 53^a in the periphery of the cam disk 53 so that for every ten revolutions 15 of the shaft 14 there will be one revolution of the shaft 15. The shaft 15 is also provided with a tooth disk 54, the tooth 54^a of which is adapted to coöperate with the slots 55^a in the periphery of the cam disk 55 secured upon the shaft 16, the arrangement being such that the shaft 16 will make one revolution for every ten revolutions of the shaft 15. It will be seen that the disks 20 on the shafts 15 and 16 carry the digits from 25 "1" to "0," while the disk 20 on the shaft 14 carries the fractions in eighths. This is because of the particular showing that I am making herein, since, as I have said, I contemplate the use of my invention particularly in connection with a time keeping organization. Thus, let it be presumed that the shaft 28 will be actuated by the device 30 to make a half revolution every seven and a half minutes. Also let it be presumed that 35 such a half revolution will cause one-eighth of a revolution of the gear 46. Thus, the wiper on the shaft 14 is advanced one-eighth of a revolution every seven and one-half minutes. There are eight equally spaced 40 contacts 23 in association with the fraction shaft and thus the fraction wiper is moved from one contact to another, step by step, when the gear 46 is in contact with the pinion 52. There are ten contacts 23 equally spaced about the shaft 15 and the wiper in 45 connection with this shaft moves from one to the next to each complete revolution of the shaft 14. There are ten contacts 23 in association with the shaft 16 and the wiper 50 on this shaft moves from one to the next for each complete revolution of the shaft 15.

In order that it may appear from the face of the bank of devices whether or not a particular device is in operative relation 55 with the driving shaft 28, I provide an indicating piece 56 which, by means of a rod 37, is carried by the armature 36. The indicator 56 is disposed in the rear of a window 58 in the cover 25 and it appears directly behind such window, exposed to view, when the armature 36 is thrown out in the dotted position shown in Fig. 4. When the armature 36 is drawn up, the indicator is hidden, as illustrated, and one may know

from the front of the board that the gears 85 are in mesh.

In order that the wipers may be set independently of each other, I provide a special arrangement for the shaft 15 as illustrated in Fig. 7. The shaft 15 is capable of longitudinal movement in the bearing 13, but under normal conditions this longitudinal movement is overcome by a spring 59 lodged in a pocket 60 in the block 11 around the shaft 15. This spring tends to hold the disk 53 up against the bearing 13 and when so disposed the faces of the Geneva mechanism are all in operative relation, as illustrated in Fig. 2. When, however, it is desired to set the wipers independently of each other, the thumb-screw 21 is pushed inwardly and this removes the disks 54 and 53 from engagement with the disks 55 and 50 respectively, as illustrated in dotted lines in Fig. 2.

Referring now to Fig. 9, I have there illustrated diagrammatically a system in which the device of my invention is employed. The contact parts of the devices are illustrated at *c*, *c*, *c*, and the electromagnetic parts are illustrated at *e*, *e*, *e*. It is now understood that each of the electromagnetic devices *e* has two magnets, one of which throws the contact mechanism into operative relation with the shaft 28 and the other of which removes it. I provide a switch plate 85 *S* upon which a plurality of switches *s*, *s*, are mounted. The movable elements of these switches are all connected to one pole of the battery and the other pole of this battery is connected to one terminal of each of the electromagnets 34 and 35. The other terminal of the magnet 35 is connected with the "in" contact *i* of one of the switches and the other terminal of the winding 34 is connected with the "out" contact of the switch. 100 There is a switch *s* for each device *e*. Each of the contacts 23 is connected with the printing electromagnet and if it is desired to print a certain number when the wiper is in engagement with a certain contact, the printing electromagnet of that same denomination is connected with that contact, one terminal being connected with the contact and the other with the wiper. I have shown such a printing electromagnet at *p* and have 105 shown a battery in this circuit. A switch *s* is assigned to each employee and when he begins work he closes the "in" circuit and that throws the particular accumulator in that circuit into operative relation with the driving mechanism. When he stops work he closes the "out" circuit and this removes his accumulator from the driving mechanism. As this goes on, the contact mechanism is gradually advanced step by step and 110 when it is desired to obtain a record of the time spent by any particular employee, the printing electromagnets may be operated 115

and those connected in circuit, will respond. It is clear that regardless of the printing electromagnets, the amount of time accumulated by an employee can be read on the plate of the bank of accumulators.

It is my idea to operate all the devices from the central motive device and this may be either mechanical or electromagnetic.

I claim as new and desire to secure by Letters Patent:

1. In electrical circuit changing mechanism, a series of contacts, a wiper for said contacts, means for moving said wiper, electromagnetically operated means for controlling said wiper, a manually controlled switch for causing actuation of said electromagnetic controlling means, a second series of contacts, and a wiper for said second series kinematically connected with the first named wiper.

2. In electrical circuit changing mechanism, a series of circularly arranged contacts, a rotary wiper for said contacts, means for moving said wiper, electromagnetically operated means for controlling said wiper, a manually controlled switch for causing actuation of said electromagnetic controlling means, a second series of contacts, a wiper for said second series, means kinematically connecting said wipers so that the last named wiper will make one revolution for every ten of the first named, a third series of contacts, a wiper for said third series, and means for kinematically connecting the third wiper with the second so that the latter will make one revolution for every ten of the former.

3. In electrical circuit changing mechanism, three series of circularly arranged contacts, a rotary wiper for each of said series, Geneva mechanism connecting said wipers, and means to move the middle element of said mechanism only out of the zone of the other two, to permit independent setting of said wipers.

4. In electrical circuit changing mechanism, a shaft, means for rotating said shaft, a pinion on said shaft, a gear, electromagnetic means for bringing said gear into and out of mesh with said pinion, a series of circularly arranged contacts, and a wiper rotating with said gear and riding on said contacts.

5. In electrical circuit changing mechanism, a shaft, means for rotating said shaft, a pinion on said shaft, a gear, electromagnetic means for bringing said gear into and out of mesh with said pinion, a series of circularly arranged contacts, a wiper rotating with said gear and riding on said contacts, means for automatically locking the gear and pinion in engagement, and

electromagnetic means for releasing said gear from said pinion.

6. In electrical circuit changing mechanism, a plurality of contacts, a wiper for said contacts, periodically operated means for moving said wiper, and electromagnetically operated means for controlling said wiper.

7. In electrical circuit changing mechanism, a plurality of contacts, a wiper for said contacts, means for moving said wiper, electromagnetically operated means for controlling said wiper, and a number 75 wheel carried by said wiper.

8. In electrical circuit changing mechanism, a plurality of contacts, a wiper for said contacts, means for moving said wiper, electromagnetically operated means for controlling said wiper, and an indicator operated by said electromagnetic means to indicate the position thereof.

9. In electrical circuit changing mechanism, a series of circularly arranged contacts, a rotary wiper for said contacts, means for moving said wiper, electromagnetically operated means for controlling said wiper, a second series of contacts, a wiper for said second series, means kinematically connecting said wipers so that the last named wiper will make one revolution for every ten of the first named, a third series of contacts, a wiper for said third series, means for kinematically connecting the third wiper with the second so that the latter will make one revolution for every ten of the former, switches for controlling the circuits of said electromagnets, and printing electromagnets connected with 100 said contacts and wipers.

10. In electrical circuit changing mechanism, a plurality of circularly arranged contacts, a ring surrounding said contacts, a wiper for bridging said contacts and said ring, means for moving said wiper and means for controlling said wiper.

11. In combination, a plurality of number disks, a driving shaft, means for moving said shaft, and an individual clutch for connecting each disk with said shaft, said clutch being operated electromagnetically.

12. In electrical circuit changing mechanism, a plurality of series of contacts, a wiper for each series of contacts, common means for driving all of said wipers, and individual means for connecting each of said wipers with said driving means.

In witness whereof, I hereunto subscribe my name this 11th day of April, 1912.

ALFRED L. SOHM.
